UNITED STATES PATENT OFFICE.

PHILLIP SEYMOUR COHEN, OF BOSTON, MASSACHUSETTS.

MENU.

1,201,700.

Specification of Letters Patent. Patented Oct. 17, 1916.

Application filed January 3, 1916. Serial No. 70,011.

To all whom it may concern:

Be it known that I, PHILLIP S. COHEN, a citizen of the United States, residing at Boston, in the county of Suffolk and State 5 of Massachusetts, have invented a new and useful Menu, of which the following is a specification.

The present invention appertains generally to books, and aims to provide a novel 10 book adapted particularly for use as a menu in cafés, restaurants, and the like, although the book may be found useful for other purposes, such as theater programs and the like.

It is the object of the invention to provide 15 a menu characterized by its artistic effect, that is thoroughly sanitary, and is provided with novel means for containing advertising matter, whereby the cost of the menus can be defrayed by the receipts from 20 the advertisements.

The menu includes a plurality of permanent leaves, two of which provide the 25 covers, and replaceable paper or cardboard leaves disposed between the permanent leaves and containing the menu proper or food list, the permanent leaves embodying metallic frames or bindings carrying removable advertising panels or sheets protected by celluloid or other transparent 30 panels or sheets, whereby the advertising panels are protected so that they will not become soiled during the handling of the menu. The advertising panels can be removed and replaced from time to time, and 35 the permanent leaves are detachably hinged together, the menu leaves being disposed so that when the menu is opened, an advertisement will always be visible when the menu list or bill is exposed. The menu leaves, 40 which comprise a folded or doubled sheet, are held in place by one of the permanent leaves, and by removing said permanent leaf, the menu sheet can be removed and replaced when it becomes soiled, or when 45 the menu list is changed. This provides for the renewal of soiled menu leaves or sheets with little trouble, the permanent leaves remaining the same as before. The menu leaves are held in place simply by the hinge 50 portion of the permanent leaves, and no additional fasteners, bands, rubbers, glue, or kindred securing means are employed, thus saving material and expense. The advertising panels and transparent sheets cov-

ering them are metal bound, to prevent the 55 destruction thereof, and the panels can be readily removed to be replaced for changing the advertisements.

It is also within the scope of the invention to provide a menu of the nature indicated, which is comparatively simple and inexpensive in construction and which will serve its office in a thoroughly practical and serviceable manner.

With the foregoing and other objects in view which will appear as the description proceeds, the invention resides in the combination and arrangement of parts and in the details of construction hereinafter described and claimed, it being understood 70 that changes in the precise embodiment of the invention herein disclosed can be made within the scope of what is claimed without departing from the spirit of the invention.

The invention is illustrated in the accompanying drawing, wherein:—

Figure 1 is a perspective view of the menu with the leaves separated or opened slightly. Figs. 2, 3, 4 and 5 are plan views 80 of the leaves separated from one another. Fig. 6 is an enlarged sectional detail through the hinge taken on the line 6—6 of Fig. 1. Fig. 7 is an enlarged sectional detail taken on the line 7—7 of Fig. 2, portions being 85 broken away. Fig. 8 is an elevation of the hinge pin.

The present menu is in the form of a book having five leaves, or ten pages, and embodies the front cover leaf 1, the back cover leaf 2, and the intermediate or central leaf 3, and the menu leaves 4 and 5 disposed between the leaf 3 and the two cover leaves. The leaves 1, 2 and 3 are the permanent 90 advertisement leaves and they are of similar construction and are hinged together.

Each of the permanent leaves 1, 2 and 3 embodies a rectangular frame 6 of suitable sheet metal or other material possessing the proper qualities, and the upper and lower 100 ends of the frame 6 are provided with reflexed flanges 7, while the free or outer edge of the frame 6 is provided with a reflexed lip 8. Said lips 7 and 8 form with the frame 6 a receptacle for the advertising 105 panel or panels 9, which can be slid by an outward movement under the lips 7, or between the lips 7 and the frame 6, it being

understood, of course, that the leaves are detached when the panels 9 are removed and inserted. The opposite sides of the panels or sheets 9 are covered with celluloid, or 5 other transparent panels or sheets 10 which fit within the frame 6 the same as the panels 9, and said sheets 10 will prevent the advertising panels from being soiled by the fingers or otherwise, thus keeping the panels 10 clean. Said panels can be provided with various advertising matter, including attractive pictures or cuts, and the outer panel 9 of the front leaf 1 is preferably provided with an ornamental picture in addition to 15 a proper legend.

The panels 9 and sheets 10 are held within the frame 6, by means of bendable or pliable ears 11 with which the inner edges of the frames 6 are provided, said ears 11 being 20 bent back or reflexed to engage the inner edges of the panels 9 and sheets 10 to hold them within the frames. These ears can be readily bent and unbent.

As herein disclosed, and illustrated, the 25 frames 6 are formed from sheet metal blanks, although it is to be understood that these frames can be cast or otherwise produced without in any way altering their functions.

30 In order to hinge the leaves 1, 2 and 3 together, the inner edges of the frames 6 of the cover leaves 1 and 2 are provided adjacent the ends thereof with alining offset hinge butts 12, and the inner edges of said 35 frames are also provided between their ends with alining offset hinge butts 13, while the inner edge of the frame 6 of the central leaf 3 is provided with a pair of hinge butts 14 disposed between the hinge butts 12 and 40 13. A hinge pin 15 extends through all of the hinge butts, and therefore hinges the leaves 1, 2 and 3 together.

The menu leaves 4—5 comprise a sheet 16 of paper, cardboard or equivalent material, 45 which can be readily cut and printed, and said sheet 16 is provided along the fold line 18 between the leaves 4 and 5, with an elongated slot 17. The leaf 3 fits between the leaves 4—5, and the hinge butts 14 project 50 through the slot 17 of the sheet 16, the butts 14 abutting against the ends of the slot 17, whereby the sheet 16 is firmly held in place between the permanent leaves, and said leaves 4—5 are assembled in a hinged manner with the other leaves to swing open 55 freely.

The leaves can be readily assembled, by first placing the cover leaves 1 and 2 together, then laying the sheet 16 thereon, 60 then inserting the hinge butts 14 of the leaf 3 through the slot 17 and between the hinge butts 12 and 13 of the cover leaves, and finally inserting the hinge pin 15. The intermediate leaf 3 thus serves to hold the menu leaves 4 and 5 in place, and when the menu 65

leaves 4—5 become soiled, or out of date, they can be readily removed, simply by withdrawing the hinge pin 15 so that the leaf 3 is released, and then by removing the leaf 3, the sheet 16 can be readily removed 70 and replaced by a new one. The menu leaves 4—5 can thus be renewed from time to time with the use of the same advertisement leaves 1, 2 and 3, and it will be noted that each page of the menu leaves 4—5 faces 75 an advertisement page, whereby when any page of the menu leaves is observed, there will be an advertisement page next to it. The permanent pages are not only of advantage for containing the advertising matter, but they also serve to protect the menu leaves 4—5, and the device as a whole provides a most desirable and effective book adapted especially for use as a menu, although it can be used for theater programs, and the like, 80 the sheets 4—5 containing the program proper or other data, which can be renewed with the use of the same advertisement leaves.

The advertisements of each of the leaves 90 1, 2 and 3 may be printed on the opposite sides of a single panel, or two separate panels may be provided, whichever is desired.

Having thus described the invention, what 95 is claimed as new is:

1. A book comprising three hinged leaves, a doubled sheet providing leaves between the aforesaid leaves, said sheet having a slot at its fold line, and the intermediate leaf having a hinge portion projecting 100 through said slot.

2. A book comprising three hinged leaves, a doubled sheet providing leaves between the aforesaid leaves, said sheet having a slot at its fold line, and the intermediate leaf 105 having a hinge portion projecting through said slot, said intermediate leaf being detachable.

3. A book embodying three leaves having alining hinge butts, a hinge pin extending through said butts, and a folded sheet providing two leaves between the aforesaid leaves, said sheet having a slot at its fold line, and the intermediate sheet having a hinge 110 butt projecting through said slot.

4. A book embodying three hinged leaves, each embodying a frame and a removable panel fitted in the frame, a folded sheet providing leaves between the aforesaid leaves, said sheet having a slot at its fold line, the intermediate leaf being detachable and having a hinge portion projecting through said slot.

5. A book comprising three leaves each embodying a rectangular frame having 125 hinge butts at its inner edge and means at its upper and lower ends and outer edge for receiving a panel, said frames having bendable ears at their inner edges for holding said panels in place, a hinge pin extend- 130

ing through said hinge butts, and a folded sheet providing a pair of leaves between the aforesaid leaves, said sheet having a slot at its fold line, and the hinge butts of the intermediate leaf projecting through said slot.

In testimony that I claim the foregoing

as my own, I have hereto affixed my signature in the presence of two witnesses.

PHILLIP SEYMOUR COHEN.
